UNITED STATES PATENT OFFICE.

FREDOLF J. PETERSON, OF ALLIANCE, OHIO.

ADDING-MACHINE.

1,227,655.

Specification of Letters Patent.

Patented May 29, 1917.

Application filed June 17, 1915. Serial No. 34,620.

To all whom it may concern:

Be it known that I, FREDOLF J. PETERSON, a citizen of the United States, residing at Alliance, in the county of Stark and State of Ohio, have invented a new and useful Adding-Machine, of which the following is a specification.

My invention relates to adding machines and has for its object the provision of a new and improved adding machine which is comparatively simple and durable in construction, not liable to easily get out of order, and arranged to permit convenient manipulating with a view to add up any desired number of sums and indicate the total and more particularly add sums representing money in dollars and cents or other denominations.

A further object is to provide an adding machine of the character referred to with a clearing key arranged to clear the machine after each total is made.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims without departing from the spirit or sacrificing any of the advantages of the invention.

35 In the accompanying drawings:

Figure 1 is a perspective view of the adding machine.

Fig. 2 is a longitudinal sectional view of the same.

40 Fig. 3 is a top plan view with the cover removed.

Fig. 4 is a section on line 4—4, Fig. 3.

Fig. 5 is a section on line 5—5, Fig. 3.

45 Fig. 6 is a transverse section through the machine showing the clearing key in the operative position to clear the machine.

Fig. 7 is a detail perspective view of one of the keys.

50 Fig. 8 is a detail perspective view of one of the number wheels with its accompanying key and ratchet.

Similar numerals of reference indicate corresponding parts throughout the several figures of the drawings.

55 In the accompanying drawings the numeral 1 represents the outer casing of the

adding machine which is substantially of the form shown and is preferably provided with a removable cover 2 arranged to be attached thereto by means of screws 3 or their equivalents. The non-rotatable shaft 4 is rigidly mounted between the side walls of the casing 1 preferably by screws 5 as best shown in Fig. 2. The shaft 4 is provided with a key-way 6 and fixedly mounted upon said shaft by means of the tangs 7 located in said key-way are the spaced disks 8, each of said disks being provided with a substantially V-shaped notch 9 in its periphery, the purpose of which will be hereinafter described. 60

Located between the disks 8 and upon the outside of each of the outer disks is a number wheel 10, each of said number wheels being provided with a hub 11, a boss 12 of larger diameter than the hub being also provided upon each number wheel, said number wheels being loosely and independently mounted upon the shaft 4. Four series of numerals from 0 to 9 are provided around the periphery of each of the number wheels. 65 70 75 80 Loosely mounted upon each of the bosses 12 is the annular portion 13 of an operating key 14, said annular portion being provided with an elliptical opening 15 arranged to accommodate the boss 12. A ratchet wheel 85 90 95 100 105 110 115 118 120 125 128 130 132 134 136 138 140 142 144 146 148 150 152 154 156 158 160 162 164 166 168 170 172 174 176 178 180 182 184 186 188 190 192 194 196 198 200 into the position best shown in Fig. 6, after which the screws 5 are tightened, holding the shaft and disk 8 rigidly in position.

One of the operating keys is located 5 through each of the slots 22 in the curved portion of the cover 2. A series of numbers from 1 to 9 is located adjacent each of the slots 22 and a pointer 23 is provided upon each of the operating keys 14, said pointer being for the purpose of indicating the number to be added in each column.

A shaft 24 is carried between the side walls of the casing and mounted upon said shaft a plurality of locking pawls 25, each 15 of said pawls being arranged to engage one of the ratchet wheels 16 for the purpose of preventing back movement of said ratchet wheels and their accompanying number wheels. Each of the pawls is normally held 20 in engagement with its respective ratchet wheel by means of a coil spring 26 located in a suitable socket 27 in the rib 28, preferably formed integral with the rear wall of the casing, said coil springs bearing against the 25 tail portions 29 of the locking pawls.

A square rod 30 is provided with cylindrical bearing portions 31 and 32, which are journaled in the brackets 33 and 34, said brackets being attached to the casing in any 30 suitable manner, preferably by the screws 35 located through the rib 28. A comb 36 is connected to the square rod 30 in any suitable and well known manner such as the rivets 37, said comb being provided with a 35 series of spring fingers 38, each of said fingers being arranged to contact with the uppermost locking pawl upon the adjacent number wheel for the purpose of bringing said pawl into engagement with the adjacent 40 ratchet wheel as the tapered head 39 of said pawl is moved into the V-shaped notch 9 of the accompanying disk 8.

In order to normally hold the spring fingers 38 in engagement with the transfer pawls a coil spring 40 is carried upon the bearing end 31 of the square rod, the extremity of said spring being located between the shaft 24 and rib 28 as best shown in Fig. 4. A rock lever 41 provided with 45 a finger engaging button 42 is rigidly connected to the bearing portion 32 of the square rod for the purpose of rocking said square rod as best illustrated in Fig. 6 in order to bring these spring fingers 38 out 50 of engagement with the locking pawls as will be hereinafter described.

The following device is provided for the purpose of clearing the machine after a total has been obtained. A pair of arms 43, 60 each provided with an elongated aperture 44 are carried upon the shaft 4, one of said arms being located at each extremity of the series of number wheels, said arms being connected at their lower extremities by 65 means of a rod 45. A pair of ribs, 46

eccentric to the shaft 4 are provided upon the side walls of the casing 1, the rod 45 normally resting at the lowermost extremity of said ribs as best shown in Figs. 2 and 5, the arms 43 contacting with the 70 stop pins 47 which are located in the side walls of the casing. A centrally located, downwardly disposed arm 48 is carried by the rod 45, said arm being provided with a pin 49, which passes through a slot 50 in 75 the key bar 51, said slot being provided with a downwardly disposed portion 52 at its inner extremity and a finger engaging button 53 being provided upon the outer extremity of said key bar. A coil spring 80 54 is attached to the key bar 51 as shown and to the rear wall of the casing. The rod 45 is provided with a plurality of hooks 55 arranged to engage the posts 19 carried by the number wheels. The number wheel 85 farthest to the left in Fig. 2 is provided with four posts 56 arranged to be engaged by the adjacent hook 55 in the same manner that the posts 19 upon the other number wheels are engaged.

The operation of the machine is as follows:

Assuming that the first item to be added was 63 $\frac{1}{4}$, the operating key at the right hand end of the machine would be placed 95 in the position shown in Fig. 1, the indicator 23 thereon resting adjacent the number 3 upon the casing. At the same time the key would be pushed forward, bringing the tapered lug 57 thereon into engagement with the adjacent ratchet wheel and the key would be moved back into the normal position. The next adjacent key would then be raised into the position illustrated in Fig. 1 and operated in the same manner. 100 Each additional item would be placed in the machine in the same manner. It will be seen that from time to time as it is necessary the transfer pawls 18 as they pass the notched portion 9 in the disk 8 will engage 110 the ratchet wheel of the next adjacent number wheel to the left, moving said number wheel forward one point. It will thus be seen that the machine will add correctly any number of items placed therein as indicated. The locking pawls 25 prevent any back movement of the number wheels. It will also be understood that the sum after the addition of each item will be indicated in the enlarged apertures 58 at the upper 115 extremities of the slots 22. When a total has been obtained and it is desired to add a new account it is of course necessary to first clear the machine and this is accomplished by means of the clearing key 51. The finger button 53 is first pressed by the operator and the key bar pulled outward, sliding upon the roller 59 carried by the bracket 60. As the key bar reaches the limit of its outward movement a slight downward pres- 120 125 130

sure upon the finger button 53 will cause the key bar to fulcrum upon the roller 59, bringing the downwardly disposed portion 52 of the slot into engagement with the pin 49. The rock lever 41 will then be depressed, raising the spring fingers 38 out of engagement with the transfer pawls and the key bar 51 will then be moved into the position shown in Fig. 6, the rod 45 riding upon the eccentric ribs 46 moving the hooks 55 into engagement with the posts 19, bringing all of the number wheels into the normal position. The clearing key will then be moved back into its normal position, disengaging the pin 49 from the downwardly disposed portion 52 of the slot therein, the spring 54 holding the clearing key in its normal position.

I claim:

1. In an adding machine of the character described, the combination of a casing, a shaft fixed to and carried by said casing, a series of number wheels loosely mounted upon said shaft, each of said number wheels being provided with a hub, a ratchet wheel fixedly mounted upon the hub of each number wheel and spaced from said number wheel, a disk provided with an elongated aperture mounted upon the hub of each number wheel between said number wheel and said ratchet wheel, an operating key rigidly connected to each disk and a tapered lug carried by each operating key and arranged to engage the accompanying ratchet wheel.

2. An adding machine comprising a series of number wheels, manually controlled means for turning the number wheels independent one of the other, a ratchet wheel for each number wheel, sidewise projecting pawls carried by the number wheels and arranged to engage the ratchet wheel of the next following number wheel in the series, fixed disks arranged between and concentric with the number wheels, each disk normally holding the corresponding pawls out of engagement with the next following ratchet wheel, the disks having a notch for allowing the pawls to move into engagement with the ratchet wheels, a rock bar located adjacent said number wheels, spring fingers carried by said rock bar and arranged to normally hold said pawls in engagement with the peripheries of said disks and means for rocking said rock bar to move said spring fingers out of engagement with said pawls, and means for moving all of said number wheels for the purpose of clearing the machine.

3. An adding machine comprising a series of number wheels, manually controlled means for turning the number wheels independent one of the other, a ratchet wheel for each number wheel, sidewise projecting pawls carried by the number wheels and arranged to engage the ratchet wheel of the next following number wheel in the se-

ries, fixed disks arranged between and concentric with the number wheels each disk normally holding the corresponding pawls out of engagement with the next following ratchet wheel, the disks having a notch for allowing the pawls to move into engagement with the ratchet wheels, a rock bar located adjacent said number wheels, spring fingers carried by said rock bar and arranged to normally hold said pawls in engagement with the peripheries of said disks and means for rocking said rock bar to move said spring fingers out of engagement with said pawls, and means for moving all of said number wheels for the purpose of clearing the machine.

4. In an adding machine of the character described, the combination of a casing, a shaft fixed to and carried by said casing, a series of toothed number wheels loosely mounted upon said shaft, the periphery of each of said number wheels being provided with a plurality of series of figures from 0 to 9, a cover provided with slots, said cover also provided with figures near the edges of said slots, a series of disks located between said number wheels and fixedly mounted upon said shaft, each of said disks provided with a notch in its periphery, a plurality of transfer pawls carried by the number wheels, one of said pawls being provided for each series of numbers from 0 to 9 upon each number wheel, said transfer pawls arranged to travel around the periphery of said disks, springs arranged to throw said pawls into said recesses, means for moving said springs out of engagement with said pawls, a pair of slotted arms mounted upon said shaft, a rod fixedly connected to said arms, hooks upon said rod arranged to engage said number wheels and a key bar connected to said rod and arranged to oscillate the same.

5. In an adding machine of the character described, the combination of a casing, a shaft fixed to and carried by said casing, a series of toothed number wheels loosely mounted upon said shaft, the periphery of each of said number wheels being provided with a plurality of series of figures from 0 to 9, a cover provided with slots, said cover also provided with figures near the edges of said slots, a series of disks located between said number wheels and fixedly mounted upon said shaft, each of said disks provided with a notch in its periphery, a plurality of transfer pawls carried by the number wheels, one of said pawls being provided for each series of numbers from 0 to 9 upon each number wheel, said transfer pawls arranged to travel around the periphery of said disks, springs arranged to throw said pawls into said recesses, means for moving said springs out of engagement with said pawls, a pair of slotted arms mounted upon said shaft, a rod fixedly connected to said arms, hooks upon said rod arranged to engage said number wheels and a key bar connected to said rod and arranged to oscillate the same.

2
arms mounted upon said shaft, a rod fixedly connected to said arms, hooks upon said rod arranged to engage said number wheels and a key bar connected to said rod and arranged to oscillate the same and curved ribs located upon the side walls of said casing and eccentric to said shaft, said ribs being for the purpose of guiding said rod.

6. In an adding machine of the character described, the combination of a casing, a shaft fixed to and carried by said casing, a series of number wheels being provided with a hub, a ratchet wheel fixedly mounted upon the hub of each number wheel and spaced from said number wheel, a disk provided with an elongated aperture mounted upon the hub of each number wheel be-

tween said number wheel and said ratchet wheel, an operating key rigidly connected to each disk, a tapered lug carried by each operating key and arranged to engage the accompanying ratchet wheel, a rock bar located adjacent said number wheels, means carried by said rock bar and arranged to normally hold each of said number wheels in operative engagement with the next adjacent ratchet wheel, means for rocking said rock bar for disengaging said number wheels from said ratchet wheels and means for moving all of said number wheels for the purpose of clearing the machine.

In testimony that I claim the above, I have hereunto subscribed my name.

FREDOLF J. PETERSON.
